CLAIM

The ornamental design for a combined shelf adapter and holder for electronic labels, as shown and described.

DESCRIPTION

FIG. 1 is a right side view of a combined shelf adapter and holder for electronic labels in accordance with a preferred embodiment of my design, the left side being a mirror image thereof;

FIG. 2 is a front elevation view of the combined shelf adapter and holder for electronic labels of FIG. 1;

FIG. 3 is a rear elevation view of the combined shelf adapter and holder for electronic labels of FIG. 1;

FIG. 4 is a top plan view of the combined shelf adapter and holder for electronic labels of FIG. 1;

FIG. 5 is a bottom view of the combined shelf adapter and holder for electronic labels of FIG. 1;

FIG. 6 is a right side view of a shelf adapter extrusion of the combined shelf adapter and holder for electronic labels of FIG. 1, the holder for electronic labels removed for clarity of illustration, the left side being a mirror image thereof;

FIG. 7 is a front elevation view of the shelf adapter extrusion of FIG. 6;

FIG. 8 is a rear elevation view of the shelf adapter extrusion of FIG. 6;

FIG. 9 is a top plan view of the shelf adapter extrusion of FIG. 6;

FIG. 10 is a bottom view of the shelf adapter extrusion of FIG. 6;

FIG. 11 is a right side view of a holder extrusion of the combined shelf adapter and holder for electronic labels of FIG. 1, the shelf adapter removed for clarity, the left side being a mirror image thereof;

FIG. 12 is a front elevation view of the holder extrusion of FIG. 11;

FIG. 13 is a rear elevation view of the holder extrusion of FIG. 11;

FIG. 14 is a top plan view of the holder extrusion of FIG. 11; and,

FIG. 15 is a bottom view of the holder extrusion of FIG. 11. The dashed lines shown in the figures represent environmental subject matter and form no part of the claimed design.
